CONTROL PANEL FOR A WASHING MACHINE OR THE LIKE

Montgomery Ferar, Huntington Woods, Mich., assignor
to Whirlpool Corporation, St. Joseph, Mich.

Filed July 6, 1959, Ser. No. 56,654

Term of patent 14 years

(Cl. D49—1)

FIGURE 1 is a front perspective view of a control panel for a washing machine or the like showing my new design. The other side not shown is substantially like the side shown and the back is substantially plain.

FIGURE 2 is a front elevational view thereof;

FIGURE 3 is a vertical sectional view thereof taken along line 3—3 of FIGURE 2; and

FIGURE 4 is a vertical sectional view thereof taken along line 4—4 of FIGURE 2.

I claim:

The ornamental design for a control panel for a washing machine or the like, shown and described.
